DESIGN FOR A COMBINED MEMORANDUM PAD, PENCIL AND RECEPTACLE THERE- FOR

Samuel Brodsky, Brooklyn, N. Y.

Application April 12, 1940, Serial No. 91,645

Term of patent 7 years

To all whom it may concern:

Be it known that I, Samuel Brodsky, a citizen of the United States of America, residing in Brooklyn, in the county of Kings and State of New York, have invented a new, original, and ornamental Design for a Combined Memorandum Pad, Pencil and Receptacle Therefor, of which the following is a specification, reference being had to the accompanying drawings, forming part thereof.

Fig. 1 is a front elevational view of a combined memorandum pad, pencil and receptacle therefor, showing my new design; and

Fig. 2 is a side perspective view, thereof.

The opposite side of Fig. 1 is substantially plain.

I claim:

The ornamental design for a combined memorandum pad, pencil and receptacle therefor, as shown and described.

SAMUEL BRODSKY.
